UNITED STATES PATENT OFFICE.

FREDRICK W. DAVIDSON, OF ABILENE, KANSAS.

SASH-FASTENER.

1,130,151.

Specification of Letters Patent.

Patented Mar. 2, 1915.

Application filed May 19, 1914. Serial No. 839,490.

To all whom it may concern:

Be it known that I, FREDRICK W. DAVIDSON, a citizen of the United States, residing at Abilene, in the county of Dickinson and State of Kansas, have invented certain new and useful Improvements in Sash-Fasteners, of which the following is a specification.

This invention relates to new and useful improvements in sash fasteners, and has for its principal object to provide a device which will hold a window against movement in any desired position.

Another object of the invention is to provide a simple and effective sash fastener which may be easily and quickly put in place without materially changing the construction of the window.

A further object of the invention is to provide a device which will lock the upper and lower sashes in place in such a way as to prevent a person or persons from entering the house through the window and still permit the window to be adjusted for ventilation.

With these and other objects in view, the invention consists in the novel combination and arrangement of parts which will be fully set forth in the following specification and accompanying drawings, in which,

Figure 1 is a view of the interior of a window showing the fastener in place, Fig. 2 is a vertical section taken on line 2—2 of Fig. 1. Fig. 3 is a view of the window casing showing the fasteners in place. Fig. 4 is an edge view of the sashes, Fig. 5 is a horizontal sectional view of the fastener taken on line 5—5 of Fig. 3, and Fig. 6 is a vertical section taken on line 6—6 of Fig. 3.

Referring now to the drawings by characters of reference, the numeral 1 designates the wall of a building in which the window casing 2 is placed. This window casing 2 is provided with the usual slidable sashes 3 and 4 which are glazed in the usual way.

The sashes 3 and 4 above mentioned include the usual frames 5 which are grooved as at 6, and secured to the grooved edges are the cover plates 7 which are provided with a plurality of spaced transverse slots 8, which are designed to receive the locking plungers which will be more fully herein-after described. A plurality of fasteners 9 which may be of any preferred type, are provided and are arranged to extend through the cover plates 7 to hold the same

in place. The window frame 2 is pivoted with the recess 10 in the bottom wall of which is formed the transverse slots 11 which are arranged to receive the guides 12, in which the locking members, which will be more fully herein-after described, are slideable. A pair of similar slots 13 are formed in the bottom wall of the recess and are arranged to form guides for the operating plungers as shown in Figs. 3 and 5. Secured to the bottom wall of the recess 10 is a suitable angle bracket 14 which is preferably located centrally of one pair of slots 11 and 13 as shown in Fig. 3. Pivoted as at 15 to the upper terminal of the angle bracket 14 is the lever 16, one end of which is pivoted as at 17 to the locking plunger 18 which is slideable in the guide 12 hereinbefore described. A similar angle bracket 19 is provided and carries at its free terminal 70 the lever 20 having the plunger 21 pivotally mounted thereon. This lever is preferably slotted as at 22 to provide for longitudinal movement and easy operation of the device. The opposite end of the lever 20 is slotted 75 as at 23 and is arranged to receive the pivot 24 by means of which the operating plunger 25 is pivotally connected to the lever. This operating plunger is provided with the reduced extension 26 which forms the lateral 80 shoulder 27, the use of which will appear upon referring to Fig. 5. A suitable knob or gripping member 28 is carried by the free terminal of the reduced extension and is arranged to form a hand hold by 85 means of which the operation of the device is controlled. A similar operating plunger 29 is pivotally connected to the free terminal of the lever 16 and said plunger carries at its reduced end the knob 30 to 90 form a hand hold.

It will be evident from the foregoing that in use when it is desired to adjust the window, the knobs 28 and 30 are pulled outwardly, thus withdrawing the locking plungers 18 and 21 from their respective sashes and permitting the sash to be slid to the desired position. When the window has been properly adjusted the locking plungers are then forced into their respective slots thus 105 holding the windows against movement.

While in the foregoing there has been shown and described the preferred embodiment of this invention, it is to be understood that such changes may be made in 110

the combination and arrangement of parts as will be within the spirit and scope of the invention as defined in the appended claim.

Having thus described my invention, I claim:

A sash fastener including the combination with a window frame, sash slideable in the frame, said sash being grooved and an apertured plate covering the groove, of a fastening device including a plate carried by the window frame, said plate being provided with apertures near its opposite edges, a support secured intermediate the ends of the plate, a lever pivoted to the support, said lever being slotted near each end, a tubular guide secured to the plate near one edge, said guide registering with the aperture ad-

jacent said edge, a locking pin slideable in the guide, a pivot pin extending through the slot in the end of the lever and into the locking pin to pivotally and slidably hold the locking pin in operative position, a link connected to the opposite end of the lever, said link being notched and arranged to engage one of the side walls of the aperture adjacent the opposite edge, and a thumb piece carried by the link to enable the user to control the operation of the device.

In testimony whereof I affix my signature in presence of two witnesses.

FREDRICK W. DAVIDSON.

Witnesses:

O. P. FENTON,
H. R. KUGLER.
